UNITED STATES PATENT OFFICE.

GEORGE SANFORD LEE, OF HAWTHORNE, NEW JERSEY, ASSIGNOR TO
FRED W. WENTWORTH, OF PATERSON, NEW JERSEY.

GRATE-BAR.

SPECIFICATION forming part of Letters Patent No. 641,124, dated January 9, 1900.

Application filed August 29, 1899. Serial No. 728,832. (No model.)

To all whom it may concern:

Be it known that I, GEORGE SANFORD LEE, a citizen of the United States, residing at Hawthorne, in the county of Passaic and State of New Jersey, have invented certain new and useful Improvements in Grate-Bars; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to apparatus for promoting combustion; and it has reference particularly to an apparatus described, illustrated, and claimed in another and copending application filed by me October 24, 1899, which application is a division of this my present one.

The object of the invention is to provide an improved form of hollow grate-bar. This grate-bar, though I prefer to use it in connection with my improved combustion apparatus above referred to, may be used in other combustion apparatus. Therefore, though I illustrate and describe my improved grate-bar in connection with my peculiar furnace construction, I wish it to be understood that I am not limited correspondingly.

My invention therefore consists in an improved form of hollow grate-bar and in the combination and arrangement of the parts thereof, substantially as will be hereinafter pointed out, and finally embodied in the clauses of the claim.

The invention is fully illustrated in the accompanying drawings, wherein—

Figure 1 is a sectional view of a furnace of the steam-boiler class constructed after the principles disclosed in my above-mentioned copending application and embodying my improved form of grate-bar. Fig. 2 is an enlarged view, in side elevation, of two of my improved hollow grate-bars connected. Fig. 3 is a longitudinal sectional view of one of said grate-bars. Figs. 4 and 5 are transverse sectional views on the lines $\alpha\alpha$ and yy , respectively, in Fig. 2. Fig. 6 is a top plan view of two of my improved grate-bars arranged side by side as when in position in the furnace,

certain parts thereof being broken away; and Fig. 7 is a perspective view of one of a series of certain blocks or bricks used in my improved furnace for dispersing the gases that are unconsumed in the initial combustion-chamber.

In said drawings, a designates the exterior wall structure of the furnace, the same being of any well-known construction and being provided at its front end with the usual fuel-supply and ash-pit doors a' and a'' , respectively.

b is the bridge-wall, which extends transversely across the furnace, said bridge-wall and another wall (hereinafter described) dividing the same into two compartments. Upon the bridge-wall and otherwise supported in the wall structure of the furnace rests the boiler b' , whose flues communicate with the interior of the furnace at their rear ends and with the stack b'' of the furnace at their other ends.

c is a plate, preferably of metal, that extends horizontally across the front of the furnace between the fuel-supply and ash-pit doors, its inner edge being provided with a flange c' , upon which rests the front ends of the grate-bars c'' , the rear ends of said grate-bars being supported upon a girder c'' , extending across the furnace. The front ends of other grate-bars c'' , preferably arranged in alinement with the grate-bars c'' , also rest on the girder c'' , their rear ends being set in an opening or individual openings c'' that are provided in the bridge-wall. The structure comprising the plate c and the series of grate-bars, it will be seen, divides the forward compartment of the two above referred to into the ash-pit d and what I term an "initial" combustion-chamber d' . The other of the two compartments referred to is designated by the reference character d'' and constitutes a "secondary" combustion-chamber.

Each grate-bar is constructed hollow, having a channel formed therein that extends throughout the bar and has both ingress and egress openings at the same end of the bar—that is to say, at the rear end thereof. When two or more bars are used, as the bars c'' and c'' , above referred to and shown in the drawings, they are disposed in tandem arrange-

ment, the egress-opening of the one communicating with the channel of the other at the front end thereof, so that there is thus formed a single channel throughout the two bars, having two feed or ingress openings and a single egress-opening at its rear end.

Above the openings c^5 , in which the rear ends of the grate-bars c^4 rest and with the channels in which they have communication, 10 there is provided in the bridge-wall b an opening e , which extends across the furnace from one side wall to the other thereof. This opening is cut up into a number of smaller openings by a series of vertically-disposed blocks 15 e' , preferably constituting bricks of fire-clay, which have the edges thereof adjacent the initial combustion-chamber beveled off, as at e^2 . The object of providing these blocks e' is to effect a thorough breaking up and dispersing of the gases that are evolved in the 20 primary combustion that is carried on in the initial combustion-chamber d' and which are forced out through the opening e into the secondary combustion-chamber. By beveling 25 the blocks the agitation of these gases will be materially augmented, as will be apparent.

Upon the pier f , which I have formed at the bottom of the furnace and which extending across the same constitutes a portion of the 30 bridge-wall b , I erect back of said bridge-wall a deflecting-wall f' , which is slightly spaced from said bridge-wall and has its top surface inclined so that the lower edge f^2 (which is its front one) thereof is about in a horizontal 35 plane that is midway between the openings e and c^5 , respectively. The rear edge f^3 of this wall is approximately as high as the top of the opening e , and in approximate vertical alinement with it is the front lower edge f^4 of 40 a wall f^5 , that spans the furnace-chamber. A narrow opening f^6 is thus formed.

It will be seen that the bridge-wall and the structure comprised in the deflecting-wall f' and the wall f^5 together separate the furnace-space into two compartments, of which the one comprises a primary combustion-chamber and the ash-pit and the other constitutes the secondary combustion-chamber. Furthermore, the bridge-wall being spaced from the 50 structure comprising the other two walls combines therewith to form what I term a "mixing-chamber" f^8 .

It will be seen that in the operation of the furnace above described the combustion of the fuel that is placed upon the grate-bars is supported by the air which is admitted from the ash-pit between the grate-bars, and simultaneously air enters from the ash-pit the ingress-openings of the channels of the several 55 grate-bars and being conducted back and forth through each grate-bar passes out of its egress-opening and the opening c^5 in the bridge-wall, whereupon it is deflected upwardly by the deflecting-wall f' . Now as the 60 gases that are evolved but not consumed in the primary combustion above referred to are driven out of the initial combustion-chamber

they are thoroughly broken up and agitated by the beveled blocks e' and after passing said blocks are commingled in the mixing-chamber f^8 with the rising bodies of air that are discharged by the hollow grate-bars and are passing out of the openings c^5 of the bridge-wall. Thereupon the secondary combustion begins to take place, and it is promoted not only because the deflecting-wall, and the wall f^5 , together with the bridge-wall, form a mixing-chamber, as f^8 , for which there is egress for the elements of combustion only through a confined opening, but because in 80 passing through the grate-bars and being thereby brought into close proximity to the combustion that is going on in the initial combustion-chamber the temperature of the fresh bodies of air that are supporting this 85 secondary combustion has been raised, and consequently they quite readily release their oxygen.

It should be remarked that in order to best give the gases and other products of combustion that are passing out of the initial combustion-chamber proper direction, so that they will move out with facility, the bricks of which the bridge-wall is composed should be disposed so as to successively overhang each 95 other, as at f^7 .

So far as the grate-bars are concerned, any construction in which the grate-bars are hollow will suffice so long as that by it the temperature of the air as it passes through said 100 grate-bars may be materially raised. I prefer, however, to use that form of grate-bar which I will hereinafter particularly describe.

Between the bridge-wall b and the deflecting-wall f' one side wall may have an opening g , whereby refuse that collects there may be removed. The pit g' , formed by the space between these walls, may be as deep as desired, the said opening being arranged, preferably, at the bottom of it.

My improved form of hollow grate-bar shown in Figs. 2 to 6, inclusive, of the drawings comprises two sections, one of which, h , is tubular, is open at both ends, and has a further opening h' in its under side and near 115 one end, and the other of which, h^2 , is trough-shaped and receives the section h and has an opening h^3 at one of its ends. Its channel, furthermore, has communication with the section h through the opening h' near the other 120 of its ends. In cross-section the section h is substantially wedge-shaped, and it rests in similarly-shaped sockets h^4 , formed in projections i^2 , extending from the ends of the section h^2 . The upper edges of the sides of the 125 section h^2 are flat, as at i^2 , and both side surfaces of the section h are provided with longitudinal flanges i^3 , which rest upon said flat edges. The cross-sectional form of the section h should by preference be V-shaped. This appears from what is shown in Fig. 5 at i^4 .

Each grate-bar may be provided at one or both sides with spacing-lugs. These lugs are

shown in the drawings as being mounted on the section h near the ends and near the center thereof and on the section h^2 near one end thereof. Said lugs are designated by the reference character j .

In order to feed upwardly to the fuel some of the air that is passing through the grate-bars, I provide orifices k , which penetrate the section h and are inclined slightly downwardly toward the exterior of said section and which pass out of the grate-bar at the exterior line of juncture between its two sections, thereby cutting away, as at k' , a portion of the section h^2 . It will be seen that the flange 15 l^2 overhangs each of the cut-out portions k' , forming the exterior of each orifice, thus acting as a hood, as it were, to prevent dust, &c., that drops from the top of the grate-bar from clogging the orifice.

Extending from the projection i at the front end of the section h is a rectangular socket k^2 . This socket is adapted to receive the rear end or the projection i , more accurately speaking, of the section h^2 of another grate-bar 20 when two grate-bars are used in tandem, as shown in Fig. 1. When each bar is used alone or singly, in order to close the front end of the bar a block k^3 is provided, said block resting in the socket k^2 and being secured 25 therein by a pin or bolt k^4 .

It will be seen that in the improved construction of hollow grate-bar which I have hereinbefore described the sections may not only be readily taken apart for repairs, cleaning, &c., but owing to the arrangement of 30 said sections the possibility of any appreciable and undesirable leakage is obviated. Furthermore, my improved grate-bar is very simple and durable in construction and is so formed that with the least possible change in its structure it may be used either singly or 35 in tandem with other grate-bars of similar construction.

Having thus fully described my invention, what I claim as new, and desire to secure by 45 Letters Patent, is—

1. A grate-bar consisting of two members or sections, one of said members being substantially tubular and the other of said members receiving said first-named member, said 50 members having communication with each other and each having exterior communication at one of its ends, substantially as described.

2. A grate-bar consisting of two members, 55 one of said members being substantially tubular and the other of said members having a longitudinal groove receiving said first-named member, said members having communication with each other and each having 60 exterior communication at one of its ends, substantially as described.

3. A grate-bar consisting of two members, one of said members being substantially tubular and the other of said members being 65 substantially trough-shaped, said first-named member being disposed against the open side of the other member and having communication therewith and both of said members being open at the same end of the grate-bar, substantially as described.

4. A grate-bar consisting of two interlocking hollow members disposed the one above the other and communicating with each other, the upper member having downwardly-inclined orifices extending through its side wall 75 and both of said members being open at the same end of the bar, substantially as described.

In testimony that I claim the foregoing I have hereunto set my hand this 15th day of August, 1899.

GEORGE SANFORD LEE.
